UNITED STATES PATENT OFFICE.

WILLIAM M. SMITH, OF WEST MERIDEN, CONNECTICUT, ASSIGNOR TO
MERIDEN BRITANNIA COMPANY, OF SAME PLACE.

DESIGN FOR COFFIN-HANDLES.

SPECIFICATION forming part of Design No. 11,652, dated February 10, 1880.

Application filed January 7, 1880. Term of patent 14 years.

To all whom it may concern:

Be it known that I, WM. M. SMITH, of West Meriden, in the county of New Haven and State of Connecticut, have invented a new 5 Design for Coffin-Handles; and I do hereby declare the following, when taken in connection with the accompanying drawings and the letters of reference marked thereon, to be a full, clear, and exact description of the same, 10 and which said drawings constitute part of this specification, and represent, in—

Figure 1, front view of the socket; Fig. 2, front view of one-half the handle.

This invention relates to a design for coffin-handles; and it consists in the configuration shown in the accompanying illustration, and hereinafter described.

The socket represents a panel, *a*, on which the lug *b* is arranged to receive the pivot of 20 the handle. Across the top is a bar, *c*, terminating in a tip, *d*, at each end. Over the bar is the representation of drapery as drooping down onto the panel in front and hanging in folds at each side. Above the bar is a tre- 25 foil ornament, which may be omitted. At the

lower end of the panel a tassel, *g*, is suspended, which may also be omitted.

The handle is the representation of a rope, *e*, drooping from each ear to a central connection, *f*, having the appearance of a sleeve or 30 hand-piece on the rope, all as shown in the accompanying illustration.

The socket may be used with a different handle, or vice versa, it only being essential that there shall be a handle with this socket, 35 or vice versa.

I claim—

1. The design for coffin-handle socket, consisting of the panel *a*, bar *c* across the top, and drapery hanging over the bar, with or without 40 the tassel *g*, as described, and shown in the accompanying illustration.

2. The design for coffin-handles, consisting of the rope-shaped ends *e*, with central hand-piece *f*, as described, and shown in the accom- 45 panying illustration.

WILLIAM M. SMITH.
